Warren D. House,
His ATTORNEY.

UNITED STATES PATENT OFFICE

PAUL D. BURGIN, OF KANSAS CITY, MISSOURI

HEAD-LAMP-RIM REMOVER

Application filed May 5, 1930. Serial No. 450,007.

My invention relates to improvements in headlamp rim removers.

The object of my invention is to provide a novel device by which the rim of an automobile headlamp may be gripped and turned easily to and from a locked position.

A further object of my invention is to provide a novel headlamp rim remover which is simple, cheap, durable, strong, not likely to get out of order, which can be easily and quickly adjusted to fit rims of different diameters, and which is easily and quickly operated, and which will not scratch or injure the rim.

15 The novel features of my invention are hereinafter fully described and claimed.

In the accompanying drawing, which illustrates the preferred embodiment of my invention,

20 Fig. 1 is a side elevation of my improved rim remover.

Fig. 2 is a top view thereof.

Fig. 3 is an enlarged section on the line 3—3 of Fig. 1.

25 Similar reference characters designate similar parts in the different views.

The rim remover is provided with two rim gripping members adapted to respectively grip opposite sides of a headlamp rim 1, 30 shown in dotted lines in Fig. 1.

Each gripping member comprises a flat resilient flexible strip of metal 2, having fastened to its inner arcuate side a pad 3 of relatively soft material, such as felt or canvas, and which is adapted to clamp against the periphery of the rim 1.

To one end of one strip 2 is fastened one end of a handle 4. To the corresponding end of the other strip 2 is fastened a handle 5 having through it a slot 6.

Pivoted to the handle 4 is a ratchet member 7 which extends through and is slidable in the slot 6, and which in one edge is provided with notches 8 each adapted to receive the handle 5, whereby the portions of the handles 4 and 5 so connected are releasably held from movement toward or from each other.

9 designates a connecting member, preferably a link having a longitudinal slot 10.

50 Longitudinally slidable on the said con-

necting member 9 are two supports, each comprising, preferably, a bolt 11 having a square portion 12 slidably fitted in the slot 10.

On the bolt 11 is mounted a plate 13 at one side of the link connecting member 9. Two nuts 14 are respectively mounted on the bolts 11 and are adapted to respectively bear against the plates 13, so as to hold said plates and the bolts 11 from moving from the positions to which they may be adjusted.

Two pins 15 are respectively mounted in the plates 13, and respectively pivoted to said pins 15 are two hinge members 16 which are respectively fastened to the outer sides of the ends of the strips 2 which are distant from the handles 4 and 5 respectively.

For holding the strips 2 from bending, where they are fastened to the handles 4 and 5, two braces 17 are provided. These braces are respectively fastened to the handles 4 and 5, and to the outer sides of the strips 2, at a substantial distance from the points of connection of said strips 2 with the handles 4 and 5.

In the operation of my invention, the nuts 14, or one only, are loosened, and the adjacent gripping member is adjusted relatively to the other gripping member, so that the gripping members can have the pads 3 thereof fit against opposite sides of the rim 1 which is to be loosened and removed.

The ratchet member 7 is then engaged with the handle 5 to hold the handles in proper positions, leaving the hands free to tighten the nuts 14.

The handles 4 and 5 are then gripped and forced toward each other so as to tightly engage the pads 3 with the rim 1, the ratchet member 7 being released to permit of such compression of the handles toward each other.

The handles 4 and 5 are then swung in a direction such that the rim will be freed from its locking position, and can be withdrawn from the head lamp. It is well known that rims of this type often become so tightly stuck as to prevent their being moved from the locking positions by the hands unaided.

With my invention such releasing of the rims is easily and quickly effected.

This application is a continuation, in part, of the application filed by me September 4, 1929, for an auto adjustable head light door remover, having Serial Number 390,254.

I do not limit my invention to the structure shown and described, as modifications, thereof, within the spirit of the appended claims, 10 may be made without departing from the spirit of my invention.

What I claim is:—

1. In a headlamp rim remover, a connecting member, two supports thereon, one slide- 15 able toward and from the other, means for fastening releasably said slideable support in the position to which it is adjusted, two gripping members adapted to respectively grip opposite sides of a headlamp rim, and 20 means connecting said gripping members to said supports respectively by which they can be relatively moved one toward and from the other.

2. In a headlamp rim remover, a connecting member, two supports thereon, slideable toward and from each other, means for releasably fastening said supports in the positions to which they may be adjusted, two gripping members adapted to respectively grip opposite sides of a headlamp rim, and 25 two hinges pivotally connecting said supports respectively to said gripping members in a manner such that the latter may be swung toward and from each other.

3. In a headlamp rim remover, a link having a longitudinal slot, two bolts extending through said slot and movable lengthwise thereof, two plates respectively mounted on said bolts, two nuts respectively mounted on said bolts and adapted to clamp respectively against said plates, two gripping members adapted to respectively grip opposite sides of a headlamp rim, and two hinges respectively connecting said gripping members with said plates in a manner such that said gripping members may be swung toward and from each other.

4. In a headlamp rim remover, a link having a longitudinal slot, a bolt slideable in and 50 extending through said slot, a plate on said bolt, a nut on said bolt adapted to bear against said plate to clamp the latter to said link, two gripping members adapted to respectively grip opposite sides of a headlamp rim, one of said gripping members being 55 hinged to said plate, and means for fastening the other gripping member to said link, the hinged gripping member being adapted to swing toward and from the other gripping member.

5. In a headlamp rim remover, a link having a longitudinal slot, two gripping members, each comprising a flexible resilient strap adapted to embrace one side of a headlamp rim, a handle fastened at one end to said

strip, and a brace fastened to said handle and to the outer side of said strip, two supports adjustable toward and from each other in said slot and having means for being fastened in the positions to which they are adjusted, 70 and means hingedly connecting said strips to said supports, whereby said gripping members can be swung toward and from each other.

6. In a headlamp rim remover, a connecting member, two supports longitudinally movable thereon toward and from each other, means for releasably fastening said supports in the positions to which they may be adjusted, two gripping members respectively so hinged to said supports so that they may be swung toward and from each other, and adjustable means connecting said gripping members for holding the portions so connected from moving toward or from each other.

7. In a headlamp rim remover, a link having a longitudinal slot, two supports movable in said slot toward and from each other and having means for being fastened in the positions to which they are adjusted, two gripping members respectively hinged to said supports so as to be swung toward and from each other and adapted to respectively grip opposite sides of a headlamp rim and provided each with a handle one having a slot therethrough, and a ratchet member pivoted to the other handle and extending through said handle slot and having means for releasably engaging the handle having the slot for holding it from movement in either direction from any position to which it may be adjusted with respect to said ratchet member.

In testimony whereof I have signed my name to this specification.

PAUL D. BURGIN.
